UNITED STATES PATENT OFFICE.

JAMES S. THOMPSON, OF PELHAM, NEW YORK.

MOLD.

Application filed November 20, 1923. Serial No. 675,792.

To all whom it may concern:

Be it known that I, JAMES S. THOMPSON, a citizen of the United States, residing at Pelham, in the county of Westchester and 5 State of New York, have invented certain new and useful Improvements in Molds, of which the following is a specification.

This invention relates to permanent molds for making brake shoes or other castings, 10 and its object is, generally, to increase the life and efficiency of those metal molds which have refractory sections therein forming the walls or parts of the walls of the mold cavity. 15 I have found in actual practice with molds of this general description that if the corners and edges of the refractory sections are unprotected, they are liable to chip and spall. When this happens the efficiency of 20 the mold is lessened to the extent of the chipping or spalling that has taken place, and further use of the mold will result in the production of a casting which lacks the desired configuration, and may result in 25 loss of the casting and further damage to the mold. In any event, it becomes necessary, sooner or later, to replace the damaged sections of refractory material, which involves a loss of the use of the mold during 30 repairs, as well as the cost of making the repairs.

My present invention has for its object to overcome these difficulties by protecting the refractory material against chipping and 35 spalling or other similar damage which may occur during casting operations or at other times.

To this end my invention also has for its object to provide a metal protection formed 40 by walls of the mold to enclose all except that face of the refractory material which constitutes a part of the mold cavity.

And the invention also has for its object to accomplish the desired results hereinbefore indicated by providing ribs on the 45 mold sections at the parting line between the cope and the drag to form a protection for the refractory material which would otherwise be exposed at the parting line.

My invention can be embodied in permanent molds of various kinds for making different varieties of brake shoes or other castings, and I have selected a brake shoe mold for illustrating the invention in se-

lected embodiments in the accompanying 55 drawings, referring to which—

Fig. 1 is a longitudinal sectional view of a mold adapted for casting a brake shoe and embodying my invention.

Figs. 2 and 3 are transverse sectional 60 views on the lines 2—2 and 3—3 respectively of Fig. 1.

Fig. 4 is also a longitudinal sectional view of a mold showing a slightly different embodiment of the invention. 65

Fig. 5 is a longitudinal sectional view illustrating still another embodiment of the invention.

Figs. 6 and 7 are transverse sectional views on the lines 6—6 and 7—7 respectively 70 of Fig. 5.

Fig. 8 is a longitudinal sectional view of a mold combining the features illustrated in Figs. 4 and 5.

Referring to the drawings, the mold comprises a cope member 10 and a drag member 11 having a pouring gate 12 conveniently disposed through which the molten metal is poured into the mold cavity 13. Interengaging shoulders 14—15 are provided on the mold members to properly align one member with relation to the other and to hold them in aligned position during the casting operation. The pouring gate is located at the right end of the mold and interengaging shoulders are located on the opposing faces of the mold members at the opposite end and at the sides of the mold. 85

My invention is adapted for use where the mold cavity walls are part refractory and part metal, as shown in Figs. 1 and 5, and also where the mold cavity walls are substantially all refractory as shown in Figs. 4 and 8. In Fig. 1 the walls of the mold cavity, at the ends 16 thereof, are left bare to chill the ends of the casting. A refractory section 17 in the drag and refractory sections 18 in the cope provide wall surfaces which will not chill the casting. A reinforcing back 19 and a steel lug 20 for 95 a brake shoe, with a lug core 21, are held by wires 22, and a cross bar 23, in proper position in the mold cavity and in the sand plug 24. As shown in Figs. 1—3, the cope forms the top, one side and one end of the 100 mold cavity, and the drag forms the bottom, one side and one end of the mold cavity; and the parting line extends down

through the pouring gate to the top of the mold at one end of the mold cavity, along the top of the mold cavity at one side thereof, and down the other end of the mold cavity to the bottom thereof and along the other side of the mold cavity at the bottom thereof.

It is desirable that all except that face of the refractory material which is exposed in the mold cavity should be protected by a facing of metal, and since portions of the refractory material in the drag would abut against the refractory material of the cope at the parting line between the drag and cope, I provide metal ribs 25 at the parting line which protect the refractory sections and form abutting surfaces between the two members of the mold. These ribs preferably taper to a comparatively narrow or thin edge where they are exposed in the mold cavity and I have found in practice that such a restricted area of metal in the wall of the mold cavity and in association with the refractory sections will not produce an appreciable chilling of the casting or to any material extent affect the same. I find it desirable and therefore provide the ribs at the parting line wherever the refractory sections would otherwise abut and this provides, in effect, recesses for the refractory material and enclosing the refractory material except where it constitutes the wall or part of the wall of the mold cavity. These ribs form a protection for the refractory sections and for the edges and corners thereof, and will prevent chipping, spalling and other damage, which, I have found in practice, will occur sooner or later to a greater or less degree unless the sections are protected. I also find it desirable to support and protect the other edges, corners or faces of the refractory material, and therefore I provide ribs 26 for the inner ends of the refractory sections 18 and undercut the recesses for said sections at 27 to support and protect the other ends thereof.

In the construction of Fig. 4 the refractory section 28 in the drag forms the entire bottom wall, as well as one entire side wall, of the mold cavity and the drag is undercut at 29 to receive and protect the ends of the section. The refractory section 28 also forms one end wall 28' of the mold section and a refractory section 30 is arranged in the cope to form the other end wall of the mold cavity. At the parting line between the cope member and the drag member the ribs 25 are provided as heretofore described. Ribs 31 are provided in the cope to support the outer ends of the refractory sections 32 and to hold them in their recesses in the cope. These ribs are located over the end lugs which are formed on a brake shoe casting and whatever chilling effect they have is of no material importance.

Fig. 5 illustrates a mold substantially like that of Fig. 1 with the refractory sections 33 in the cope supported and protected at their outer ends in undercut ends 34 of the recesses in which the sections are held, and also by the ribs 35 such as shown in Fig. 4. In this form of mold, as shown also in Figs. 6 and 7, the top and one end of the mold cavity are formed in the cope and the bottom, two sides and one end of the mold cavity are formed in the drag, so that the parting line between the mold members is at the top and one end of the mold cavity. In this construction, as in those heretofore described, the refractory sections are protected against abutting at the parting line by the provision of ribs 25 which are shown to be formed integrally with the mold members, as in the other figures of the drawings.

Fig. 8 shows a mold substantially similar to that of Fig. 4 except that the refractory sections are somewhat differently shaped. The refractory section 36 not only forms a part of the top wall of the mold cavity, but also forms the end wall 37 thereof.

I have shown and described the ribs as made integral with the mold members, which so far has proven to be the simplest and best way of making these ribs, but I would consider it within the scope of my present invention if the ribs were not made integral.

I have found in practice that satisfactory results are obtainable if the refractory material is placed in the mold members in a plastic or semi-plastic condition and dried, and this is the way I contemplate making up the mold. This is a very simple, easy and economical method of applying the plastic material, it insures a snug fit, and can be quickly completed. But the refractory sections may be provided in the form of blocks and inserted in proper position in the mold members.

I am aware that changes in the form, construction and arrangement of parts may be made without departing from the spirit and without sacrificing the advantages of the invention and I consider myself entitled to make all such changes as fairly fall within the scope of the following claims.

I claim:

1. A mold for making brake shoes and other castings, comprising a metal drag and a metal cope and having a mold cavity therein, a refractory section seated in said mold and having a face thereof forming a wall surface of the mold cavity, the remaining faces of the refractory section being protected by the metal of the mold.

2. A mold for making brake shoes and other castings, comprising a metal drag and a metal cope and having a mold cavity therein, a refractory section disposed in said mold and having its innermost face forming a wall surface in the mold cavity,

the remaining faces of the refractory material being embedded in the metal of the mold.

3. A mold for making brake shoes and other castings, comprising a metal drag 5 and a metal cope and having a mold cavity therein, a refractory section disposed in said mold and having a face thereof forming a wall surface in the mold cavity, the faces 10 of the refractory section which are adjacent the first mentioned face being embedded in the metal of the mold.

4. A mold for making brake shoes and other castings, comprising a metal drag and 15 a metal cope and having a mold cavity therein, a refractory section disposed in said mold and having a face thereof forming a wall surface in the mold cavity, the marginal edges of said face being protected by 20 the metal of the mold.

5. A mold for making brake shoes and other castings comprising a metal drag and a metal cope and having a mold cavity therein, a refractory section disposed in said 25 mold and having a face thereof forming a wall surface in the mold cavity, the several marginal edges of the refractory section being protected by metal forming a wall surface in the mold cavity.

30 6. A mold for making brake shoes and other castings, comprising a metal drag and a metal cope and having a mold cavity therein, a refractory section seated in said mold and having a face thereof forming a wall 35 surface in the mold cavity, and a rib disposed at the parting line between the drag and cope to protect a marginal edge of said face.

7. A mold for making brake shoes and 40 other castings, comprising a metal drag member and a metal cope member and having a mold cavity therein, a refractory section seated in one of said members and having a face thereof forming a wall surface 45 of the mold cavity, and a rib formed integrally with the metal of said member and disposed at the parting line of said member to protect an edge of said face forming a wall surface of the mold cavity.

50 8. A mold for making brake shoes and other castings, comprising a metal drag member and a metal cope member and having a mold cavity therein, one of said members having an undercut recess therein, and 55 a refractory section disposed in said recess and having a face thereof forming a wall surface of the mold cavity.

9. A mold for making brake shoes and 60 other castings, comprising a metal drag member and a metal cope member and having a mold cavity therein, one of said members having an undercut recess therein, and a refractory section disposed in said recess and having a face 65 thereof forming a wall surface of the mold

cavity, the metal adjoining the marginal edges of said face being disposed substantially flush with said face.

10. In a mold for making brake shoes and other castings comprising a metal drag 70 and a metal cope and having a mold cavity therein, interengaging shoulders formed on the parting surfaces of the cope and the drag to hold them in aligned position during the casting operation. 75

11. In a mold for making brake shoes and other castings, comprising a metal drag and a metal cope and having a mold cavity therein, interengaging shoulders formed on 80 abutting faces of the cope and the drag to hold the cope and drag in aligned position during the casting operation.

12. In a mold for making brake shoes and other castings, comprising a metal drag and a metal cope and having a mold cavity therein, interengaging shoulders formed on the parting surfaces of the drag and the cope to prevent lateral displacement of the cope 85 relative to the drag during the casting operation. 90

13. A mold for making brake shoes and other castings, comprising a metal drag and a metal cope and having a mold cavity therein, the parting line between the drag and cope being located between relatively thin ribs 95 on the drag and cope. 100

14. A mold for making brake shoes and other castings, comprising a metal drag and a metal cope and having a mold cavity therein, recesses in said drag and cope, refractory sections disposed in said recesses to form wall surfaces for the mold cavity, and relatively thin metal ribs on the drag and cope to protect the marginal edges of said refractory sections. 100

15. A mold for making brake shoes, comprising a metal drag and a metal cope and having a mold cavity therein, a refractory section forming a wall surface for the mold cavity, and a metal protector overlying that 105 part of the refractory section wherein the end lug of the shoe is formed.

16. A mold for making brake shoes and other castings, comprising a metal drag and a metal cope and having a mold cavity therein, the drag having a recess projecting beyond the ends of the mold cavity, and a refractory section seated in said recess and forming a wall surface for the mold cavity. 110

17. A mold for making brake shoes and other castings, comprising a metal drag and a metal cope and having a mold cavity therein, the drag having a recess at the bottom and at one side of the mold cavity extending beyond the ends of the mold cavity, refractory material in said recess forming wall surfaces for the mold cavity, and a metal protector for the marginal edges of the refractory material. 115 120

18. A mold for making brake shoes and 125

- other castings, comprising a metal drag and marginal edges of said refractory material, a metal cope and having a mold cavity thereat and forming abutting surfaces between the 15 in, a drag having a recess at the bottom, one drag and cope at the parting line therebetween, side and one end of said cavity, refractory tween;
- 5 material in said recess forming a wall surface 20. A mold for making brake shoes and faces for said mold cavity, and a metal other castings, and comprising a drag and a protector for the marginal edges of the re- a cope and having a mold cavity therein, ribs 20 refractory material, on the drag and cope, and refractory sec-
19. A mold for making brake shoes and faces in the drag and cope between said ribs 10 other castings, comprising a drag and a cope to form with the ribs a composite wall surface and having a mold cavity therein, refractory face for the mold cavity, refractory material forming wall surfaces for said mold cavity, and thin ribs protecting the
